UNITED STATES PATENT OFFICE.

JACOB RUBIN, OF CHARLESTON, WEST VIRGINIA.

TIME-CONTROLLED SWITCH.

1,370,488.

Specification of Letters Patent.

Patented Mar. 1, 1921.

Application filed December 28, 1918. Serial No. 268,694.

To all whom it may concern:

Be it known that I, JACOB RUBIN, a citizen of Poland, residing at Charleston, in the county of Kanawha and State of West Virginia, have invented new and useful Improvements in Time-Controlled Switches, of which the following is a specification.

The purpose of the invention is to provide a time operated mechanism in conjunction with an electric circuit closing and circuit opening device whereby electric lights and electrically operated apparatuses may be put in operation for a certain length of time and cut off of operation for a certain length of time solely by mechanical means. To this end, the invention comprises an appropriate electrical switch and a pair of arms, the one closing and the other opening the switch. These arms are operated by appropriate wheels driven by suitable timing mechanism. The wheels are provided with detachable pins each engageable with its respective arm and these pins may be set at any desired points on their particular wheel, thus making it possible to have the device close the switch for a certain length of time, then open it for a certain length of time and then close it and so on.

Further purpose of the invention is the provision of a device of this character which is simple in construction, durable and effective in operation and inexpensive to manufacture.

Other and further objects appear in the following description wherein the invention is set forth in detail.

To the exact construction in which it is shown and described, the invention is not to be restricted. The right is reserved to make such changes or alterations as the actual reduction to practice may suggest, in so far as such changes or alterations are compatible in spirit with the annexed claim.

The same numerals of reference designate the same parts throughout the several figures of drawings, wherein:

Figure 1 is a view in front elevation of the complete device.

Fig. 2 is a front elevational view with the face removed.

Fig. 3 is a rear elevational view with the back removed.

Fig. 4 is a section on the line 4—4 of Fig. 2.

Fig. 5 is a section on the line 5—5 of Fig. 3.

Fig. 6 is a perspective view of the switch opening member, this being similar but of slightly different shape from the switch closing member.

Fig. 7 is a perspective view of a modified form of switch.

As shown, the invention comprises a casting having the front and rear walls 1 and 2 behind which are positioned the open plates 3 and 4, the latter comprising appropriate frame work for the support of clock movements 5 and 6. Each movement is driven by an appropriate spring of usual character for such movements and this spring is carried on a suitable winding arbor connected by an appropriate gear train to the minute spindle, the minute spindle 7 of the movement 6 extending laterally from the plate 4 and the minute spindle 8 of the movement 5 similarly extending from the plate 3. The minute spindle 7 carries a gear 9 forming the final unit of its attendant gear train and fixedly attached to this gear there is a pinion 10, the latter meshing with a gear 11. The gear ratio of the gear 11 and pinion 10 is twenty-four to one, so that for every revolution of the minute spindle 7 there will be a twenty-fourth of a revolution for the gear 11.

The minute spindle 8 carries a gear 12 as the terminal unit of its particular gear train and mounted with this gear 12 there is a pinion 13 meshing with a gear 14, the ratio of the gear 14 to the pinion 13 being the same as the ratio of the gear 11 to the pinion 10 so that a one-twenty-fourth of a revolution of the gear 14 will be had for each revolution of the pinion 12, and its attendant spindle 8.

The gears 11 and 14 are both loosely mounted on a shaft 15 the latter being supported in appropriate bearings formed in the plates 4 and 3. The purpose and functions of these gears 14 and 11 appear hereinafter.

Provision is made for winding both movements 5 and 6 simultaneously and since these movements run in opposite directions for a purpose hereinafter appearing, it is necessary that the winding arbors of the two movements be turned in opposite directions. To this end there is mounted in appropriate

bearings formed in the plates 4 and 3 a main staff or shaft 16, one end of this shaft protruding through the front wall or face 1 where it receives a winding key 17. Between the front wall and the plate 3, the shaft 16 carries a gear 18 and this meshes with a gear 19 carried by the main shaft or winding arbor 20 of the movement 6. It will thus be observed that as the shaft 16 is turned in one direction, the arbor 20 will be turned in the opposite direction.

Between the back wall 2 and the adjacent plate 4, the shaft 16 carries a gear 21 and this meshes with an idle gear 22 carried loosely on an appropriate stud 23 set in the plate 4, this idle gear 22 meshing in turn with a gear 24 carried by the winding arbor 25 of the movement 5. Obviously the turning of the shaft 16 will result in the turning 20 of the arbor 25 in the same direction.

Mounted on the upper edges of the plates 4 and 3 there is a horizontally disposed plate 26 and this plate supports a suitable insulating switch base 27, the latter carrying an electric switch 28 to whose terminals are brought the conducting wires 29 and 30, which connect respectively to a source of electrical supply and to the electrical device to be controlled by the apparatus. The movable element of the switch 28 is provided with an insulating foot 31 at its free terminal and this foot is adapted to be engaged either on the upper face or lower face by the spring arms 32 and 33 respectively, the latter projecting laterally from rock shafts 34 and 35 which are provided with counter-balancing weights 36 and 37, whose function is to keep the arms normally out of contact with the foot 31. The rock shafts 34 and 35 are swingingly mounted in appropriate bearings formed in the front walls 1 and 2 and the latter is provided with an arm 38 positioned just back of the front wall 1 by hanging in front of the gear 14, while the former is provided with an arm 39 normally hanging in front of the gear 11 in looking at the device from the back. These arms stand just inside the rear wall 2.

Each of the gears 11 and 14 is formed with holes 40 spaced at uniform angular distance apart, the number of these holes equaling the number of hours to the day and each hole being threaded so that a pin 41 may be placed in any one desired, each hole being designated by suitable indicia to indicate a certain hour of the day.

When the device is in operation, the two gears 11 and 14 are driven in opposite directions at the rate of $\frac{1}{24}$ th of a revolution per hour. The pin 41 in the gear 14 is attached in the hole 40 designating the hour which it is desired to open the switch 29. As the gear wheel 14 is advanced, this pin eventually engages the arm 38 to rock the shaft 35 upwardly and to thus bring the arm

33 into contact with the underface of the foot 31 with the resultant raising of movable element of the switch and the separation of the circuit closing contacts. The movable element of the switch does not swing freely 70 but is frictionally engaged with its hinge posts for retaining any position to which it may be moved. Therefore, the raising operation effected by the arm 38 results in the opening of the switch. 75

The closing operation is effected by the gear 11 whose pin 41 is attached in the hole 40 bearing the hour designation at which it is desired to close the switch. This gear 11 turns in the opposite direction from the gear 14 and when its pin 41 engages the arm 39 the shaft 34 is rocked to move the arm 32 downwardly, the latter engaging the foot 31 on the upper face and forcing the movable element of the switch down to bring 85 into electrical connection the two switch contacts with the resultant closing of the circuit which the switch controls.

On the outer facing of the walls 1 and 2 appropriate dials 42 are provided bearing 90 indicia indicating the 24-hours and over these dials there are movable the hands 43 which are attached to the gears 11 and 14 respectively, the dials being formed with appropriate center openings through which 95 the hands may reach the dials for movement thereover.

In Fig. 7 there is shown a modified form of switch of the double pole variety. This switch is adapted to be used in place of the switch shown in Figs. 2 and 3 and it comprises an insulating base 50 upstanding from the top face of which there are the ears 53. Between these ears 53 there is pivotally mounted the movable element of 105 the switch and this element is provided with the foot 52 engageable above and below by the two arms mounted on the rock shafts. The movable element is bifurcated as shown and carries at the ends of its legs the contact members 55 which are brought into contact with or moved away from the contact members 54, as the movable element of the switch is rocked on its pivot by the operation of the aforesaid arms. The usual conducting wires lead from the contact points 110 54 and 55 respectively, and connect with a suitable source of electrical supply and with the mechanism or like to be controlled.

From the foregoing description and the 120 accompanying drawings, it is believed that a clear enough understanding of the invention is to be had to render further description unnecessary.

The invention having been described, 125 what is claimed as new and useful is:

A time controlled circuit closing device comprising a switch having a movable circuit control element provided with an insulating foot, a pair of rock shafts disposed re- 130

spectively in planes above and below said foot and provided with spring arms for engagement respectively with the top and bottom faces of said foot, rigid arms carried by said rock shafts, oppositely rotating wheels before each one of which one of the said rigid arms hangs, pins carried by said

wheels, the said pins being attachable to the wheels at selected points and being engageable with the said rigid arms, and mechanism rotating said wheels in the manner shown and for the purpose specified.

In testimony whereof I affix my signature.
JACOB RUBIN.
